[57] **CLAIM**

The ornamental design for a marble board game, as shown and described.

DESCRIPTION

FIG. 1 is an environmental perspective view of a first embodiment of a marble board game showing my new design;

FIG. 2 is a right side elevational view with the left side being a mirror image thereof;

FIG. 3 is a front elevational view with the rear view being a mirror image thereof;

FIG. 4 is an environmental perspective view of a second embodiment of a marble board game showing my new design;

FIG. 5 is a top plan view of the first embodiment; and,

FIG. 6 is a top plan view of the second embodiment.

The undisclosed bottom views of the boards are plain and unornamented. The right side, left side, front, and rear views are identical for each of the embodiments. The broken line showing of the frame, edges of the board, depressions, and marbles in the figures is for illustrative purposes only and forms no part of the claimed design.
